UNITED STATES PATENT OFFICE.

ROBERT E. WILSON, OF CHICAGO, ILLINOIS, ASSIGNOR TO STANDARD OIL COMPANY, OF WHITING, INDIANA, A CORPORATION OF INDIANA.

LIQUID-DISPENSING PUMP.

Application filed July 19, 1923. Serial No. 652,533.

My invention relates to devices for use in connection with liquid dispensing pumps, and more particularly gasoline pumps such as are used at filling stations, to cause the pumps to dispense a quantity or volume of the liquid according to a price named by the customer. It will be fully understood from the following description, in which a preferred form of the device is referred 10 to in connection with the accompanying drawings, in which:

Figure 1 is a side elevation, partly in section, of a form of device embodying the present invention;

Fig. 2 is a front elevation of the device, shown in both Figs. 1 and 2 in connection with parts of a gasoline dispensing pump;

Fig. 3 is a plan view of the device of Figs. 1 and 2;

Fig. 4 is a sectional view through a modified form of the device, showing a modified form of the clamp or retainer; and

Fig. 5 is a plan view of the modified form shown in Fig. 4.

The device of the present invention is employed in connection with gasoline dispensing pumps or other liquid dispensing pumps, which, have hitherto been so constructed as to provide limiting stops for the 20 operation of the pump, these stops being set to cause the pumps to dispense fixed volumes of liquid; for example, the gasoline dispensing pump at present most in use is provided with a fixed stop so arranged that the pump is caused to dispense, say, five or ten gallons of gasoline. The price of such volumes of gasoline ordinarily amounts to sums involving odd cents and their sale frequently entails inconvenience

40 and loss of time in making change and in handling small currency. In accordance with the present invention, such a dispensing pump is provided with a device whereby volumes of gasoline may be dispensed according to fixed prices named by the customer, suitable means being provided for determining the volume of the liquid dispensed in accordance with current prices of unit volumes of the liquid. In the pre-

45 ferred form of the invention illustrated in the drawings, it is embodied in a separable and readily applicable attachment which may be employed in connection with an ordinary gasoline dispensing pump set to dispense fixed volumes of gasoline, the pump

being then capable of normal use in dispensing any of such fixed volumes of gasoline, or of being immediately adaptable, by attaching my device to dispense a volume of gasoline for a stated price, while rendering inoperative the means for normally dispensing fixed volumes. 60

Referring more particularly to the drawings, the numeral 10 indicates a rigid rod forming part of an ordinary gasoline dispensing pump, and the numeral 11 a projecting lug rigidly secured to the rod 10. This fixed lug 11 is provided with a threaded opening through which passes a screw 12, the end of this screw forming the stop for 70 determining the volume of gasoline normally dispensed. The plunger rod of the pump (not shown) is provided with a projecting lug 13, which rises during the pumping operation and, at the moment the pre-determined volume of gasoline has been dispensed, engages the end of the screw 12. The position of this screw is variable, as is readily apparent, and it may be adjusted to insure accuracy of the volume of gaso- 80 line to be dispensed. 75

In the illustrated form of device for my purpose, a rod or bar 14 is provided, having graduations 15, these graduations indicating the price per gallon of the gasoline dispensed. A range of prices from 21 to 25 cents per gallon by tenths of a cent is indicated by the graduations. The bar 14 is preferably square in cross-section and may be made of any suitable material, for example, brass, duralumin, or the like. 90

The rod is provided at one end with suitable means for attaching or clamping it to the fixed stop member 11 of the pump. This may suitably be a spring clamp, formed 95 by a projecting member 16 rigidly secured as at 16^a to the bar 14 at a predetermined distance from its end, and a projecting flat spring 17 secured to the end of the bar 14, as by a screw 18. The fixed 100 projecting member 16 has formed in its upper surface a depression 19, into which the end of the fixed gallonage screw 12 is adapted to fit, as shown in Figs. 1 and 2. The fixed gallonage screw, which is provided with a notched head 20, may also be provided with a central conical projection 21, passing through an aperture in the flat spring 17. The rigid member 16 and the resilient member 17 thus form together a 105

clamp, by means of which the entire device may be readily attached to and detached from the fixed gallonage stop of the pump.

- 5 In Figs. 4 and 5 a modified form of spring retainer 17^a (corresponding to the resilient member 17 of Fig. 1) is shown, this form of retainer being adapted for use in connection with the fixed gallonage
 10 screw provided with the notched head, but not having the conical projection illustrated in Fig. 1. In Figs. 4 and 5, the numeral 12^a indicates the fixed gallonage screw, which is provided with a notched head 20^a
 15 having a flat top. The numeral 14^a indicates the upper portion of a graduated rod corresponding to the rod 14. The flat spring 17^a is shown to be secured to the top of this rod by screw 18^a, this corresponding to
 20 the mode of attachment shown in Fig. 1. To the end of the flat spring 17^a there is pivotally secured a small flat plate 17^b, which may suitably be of general triangular form, and from the bottom of this plate
 25 there depend the spaced buttons 17^c, adapted to enter adjacent notches of the head 20^a. This form of spring device may be employed in connection with flat-headed fixed gallonage screws.
 30 A second laterally projecting member 22 is slidably mounted to be adjustable upon the rod 14. This projecting member is provided on its under side with a recessed portion 23 in which is set a hardened button 24, the dimensions of the surface of
 35 which are substantially the same as those of the end surface of the fixed gallonage screw 12. This button 24 is so disposed as to be in exact alinement with the fixed
 40 gallonage screw 12, as represented in Figs. 1 and 2. The laterally projecting member 22 is also provided with a threaded opening 25, through which works an adjusting screw 26 having a notched head 27 to abut
 45 against the lower surface of the fixed laterally projecting clamping member 16. The adjusting screw 26 may be retained in any desired position by means of a lock pin 28, which is slidably set in a hole bored through
 50 the rod 14 to engage the head 27, and is held in position by means of a removable pin 29. A notch 30 is provided in the rod 14, into which the head 27 of the adjusting screw 26 partially enters. A set screw 31
 55 is provided to aid in holding the laterally projecting stop member 22 in place.

In operation, the fixed gallonage stop 12 is adjusted so that, in the normal use of the pump, a fixed amount of gasoline, say five gallons, is delivered when the member 13 is raised by the action of the pump until it engages the end of the stop. In normal operation, the pump therefore delivers, with a full stroke of the plunger, five gallons of gasoline. In instances, such as occur,

where the customer asks to have delivered to him a certain worth of gasoline, say a dollar's worth (instead of requesting a certain gallonage) and the value of which per gallon may be, for purpose of illustration, 70 22 cents, the rod 14, the movable stop member 22 on which has previously been set to the 22-cent mark on the rod, as indicated, is clamped upon the fixed gallonage screw 12 in the manner shown in Fig. 1 (or in Fig. 4). The position of the graduations on the rod 14 are calculated in accordance with the dimensions of the pump, and the stop 24 instead of the screw 12, becomes the limiting stop for the movement of the plunger rod, being engaged by the projecting member 13 at precisely the same part of the latter's surface as is engaged by the end of the screw 12 in the gallonage dispensing operation of the pump. When the stop button 24 is thus engaged, the operation of the pump is stopped, the pump having at that time delivered the volume of gasoline corresponding to the fixed price set (\$1.00). 80 85

Although the present invention has been described in connection with the specific details of a device embodying it, it is not intended that these shall be regarded as limitations upon the scope of the invention except in so far as included in the accompanying claims. 90 95

I claim:

1. In combination with a liquid dispensing pump having a fixed plunger-rod stop, a supporting member provided with a graduated scale indicating price of unit volumes of liquid, a stop device adjustably mounted on said supporting member, means for retaining said stop device in a predetermined position on the supporting member, and means for clamping the supporting member on said fixed plunger rod stop. 100 105

2. In combination with a liquid dispensing pump having a fixed gallonage stop, means for dispensing volumes according to stated prices therefor, said means including a supporting member, means for clamping the supporting member to the fixed gallonage stop, a lug slidably mounted upon said supporting member, said lug having a stop button in substantial alinement with the fixed gallonage stop, a graduated scale being provided indicating prices of unit volumes of the liquid, and means for securing the lug in a predetermined position on the supporting member in accordance with indications on the scale. 110 115 120

3. In an attachment for dispensing volumes of liquid at a stated price by means of a pump provided with a fixed gallonage stop, a rod provided with a graduated scale indicating prices of unit volumes of liquid, a lug slidably mounted on said rod, a fixed lug mounted on said rod and spaced from the end thereof, a spring member secured 125

to the end of said rod, the fixed lug and the spring member being provided with means for engaging the fixed gallonage stop of the pump, and means for retaining the 5
slidable lug in set position on the rod.

4. In an attachment for dispensing volumes of liquid at a stated price by means of a pump provided with a fixed gallonage stop, a rod provided with a graduated scale 10 indicating prices of unit volumes of liquid, a lug slidably mounted on said rod, a fixed lug mounted on said rod and spaced from

the end thereof, a spring member secured to the end of said rod, the fixed lug and the spring member being provided with 15 means for engaging the fixed gallonage stop of the pump, a threaded screw mounted on the rod and engaging a threaded opening in the slidable lug, whereby the operation of the screw changes the position of the lug, 20 and means for locking the screw in a predetermined position.

ROBERT E. WILSON.
